GUARD FOR EXTENSION LAMPS

Max Reeves, Fort Worth, Tex.

Application October 26, 1953, Serial No. 27,321

Term of patent 14 years

(Cl. D48—20)

FIG. 1.

FIG. 4.

FIG. 3.

FIG. 2.

To all whom it may concern:

Be it known that I, Max Reeves, a citizen of the United States of America, residing at Fort Worth, in the county of Tarrant and State of Texas, have invented a new, original, and ornamental Design for a Guard for Extension Lamps, of which the following is a specification, reference being had to the accompanying drawing, forming part thereof.

Figure 1 is a rear elevational view of a guard for extension lamps embodying my new design.

Figure 2 is a side elevational view thereof.

Figure 3 is a front elevational view of the new design, and

Figure 4 is a top plan view thereof.

I claim:

The ornamental design for a guard for extension lamps, substantially as shown.
